(57) **CLAIM**

The ornamental design for a flexible storage bag as shown and described.

DESCRIPTION

This application is related to co-pending U.S. Ser. No. 18/105,861, filed Feb. 5, 2023, which is incorporated herein by reference.

FIG. 1 is a bottom, front and left side isometric view of a flexible storage bag showing our new design;

FIG. 2 is a top, rear and left side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view, the right side being a mirror image thereof;

FIG. 8 is a cross-sectional view taken along line 8-8 of FIG. 3; and,

FIG. 9 is a cross-sectional view taken along line 9-9 of FIG. 3.

1 Claim, 9 Drawing Sheets
